UNITED STATES PATENT OFFICE.

HENRY HARRISON KRESS, OF PHILADELPHIA, PENNSYLVANIA.

OIL-BURNING PRESSURE TORCH.

Application filed May 28, 1923. Serial No. 641,877.

Some of the objects of the present invention are to provide an improved blow torch using as a fuel any grade of kerosene, distillate, or any other light oil readily vaporized to produce complete combustion; to provide a burner for a blow torch wherein the fuel is supplied to the burner in a highly heated vaporized condition; to provide a burner having means for preheating the fuel and producing a partially vaporized condition prior to its entering the main vaporizing chamber; to provide means for regulating and varying the fuel and air mixture to secure proper proportioning for carburetting purposes under different conditions of use; to provide a mixing tube for an oil burner which can be varied as to length and in relation to the oil inlet; to provide a fuel inlet which can be readily cleaned and maintained free of dirt and deposits; to provide a nozzle for an oil burner which is so proportioned and constructed as to prevent carbon deposits and maintain a heat zone for vaporizing purposes; to provide means for introducing a secondary air supply to an oil burning chamber; to provide a pumping element for a storage tank of a blower torch having means for causing the pump to cease functioning at a predetermined pressure; and to provide other improvements as will hereinafter appear.

In the accompanying drawings, Fig. 1 represents a longitudinal or axial section of an oil burner embodying one form of the present invention; Fig. 2 represents a side elevation of the burner and its associated parts and showing the pressure tank partly broken away; Fig. 3 represents an elevation of the discharge end of the burner; Fig. 4 represents a detail in section of the pressure release pumping element; Fig. 5 represents a detail in section of a form of safety valve; Fig. 6 represents an end elevation of Fig. 5; Fig. 7 represents a section on line 7-7 of Fig. 1; Fig. 8 represents an enlarged detail in section of the fuel control valve; and Fig. 9 represents a section on line 9-9 of Fig. 7.

Referring to the drawings, one form of the present invention comprises an oil burner 10 supplied by a pipe 11 with fuel under pressure from a storage tank 12 of a portable or any other suitable type. The pipe 11 is controlled by a main fuel valve 13 mounted in a fitting 14 which also carries a removable strainer basket 15 or other filtering means. Generally considered, the

burner 10 consists of a tubular nozzle 16, a shell or casing 17, a back plate 18 provided with a fuel mixture tube 20, and a fuel control needle valve 21.

For the purpose of heating and vaporizing the supply of liquid fuel under pressure, the nozzle 16 is constructed with a closed annular chamber 22 in its wall having an inlet 23 and an outlet 24. The fuel supply pipe 11 is connected to the inlet 23 and a vapor supply pipe 25 leads from the outlet 24 to a holder fitting 26 which, as here shown, supports at one end the supply pipe 11 and at the other end supports the vapor supply pipe 25 and a bracing or supporting pipe 27. Also the fitting 26 is provided with a passage 28 in communication with the pipe 25 and terminating in a discharge port 30 disposed to discharge axially of the shell 17 and into the fuel tube 20. It should be noted that the chamber 22 lies in close proximity to and follows the contour of the inner wall of the nozzle, and being also of relatively narrow proportions, encircling the zone of heat, it follows that the incoming fuel is subjected to a maximum heating and becomes a highly heated gaseous mixture. Furthermore, the two supply pipes 11 and 25 pass lengthwise through the shell 17 and are, thus maintained in heated condition through direct contact with the burning products so that the incoming fuel is preheated before reaching the vaporizing chamber 22 and the vaporized fuel is further heated as it returns through the pipe 25 to the burner.

In order to supply air to the hot fuel vapor, the rear end of the shell 17 is provided with the back-plate 18 which is made fast thereto and has a plurality of outwardly flaring curved openings 32 extending from adjacent a centrally disposed tubular guide 33, preferably formed as a part of the back-plate, to adjacent the outer rim of the said back-plate. Between the respective pairs of openings 32, the back-plate 18 is provided with webs or wings 34 which follow the general curved contour of the openings 32 and project into the end of the chamber formed by the shell 17. Thus the back-plate openings 32 form passages for the air to enter the shell 17 and in so doing it strikes the wings 34, is deflected substantially radially, and enters the shell proper with a swirling action.

As a means for varying and proportion-

- ing the entering air, the tube 33 carries a rotatable shutter 35 which is mounted flush with the outer side of the back-plate 18 and has substantially the same diameter. 5 This shutter 35 is provided with openings 36 similarly shaped and arranged with respect to the openings 32 of the back-plate 18 so that the shutter 35 may be brought to a position where the two sets of openings 23 10 and 36 register respectively to give the maximum supply of air, or the shutter may be turned to reduce the area of the openings and thus limit or proportion the air as desired. As the pipes 11 and 25 pass respectively through two of these sets of openings, it is desirable to provide recesses 37 so that the path of movement of the shutter 35 is unobstructed by the aforesaid pipes and can be freely swung to its limit of movement. 15 20 In order to admit a secondary supply of air, that portion of the shell 17, which encircles the fuel inlet, is provided with a plurality of apertures 38 suitably spaced and arranged to cause suction to draw in additional air to assist in promoting effective combustion.
- For initially mixing the fuel delivered from the port 30, the tube 20 is slidably mounted within the guide 33 and has an 30 outwardly flared inlet end 40 alined with the port 30 and located to receive the discharged fuel and to serve as an intake for air drawn in by the action of the fuel under pressure. This tube 20 may be moved towards or away from the port 30 so that the initial mixture may be properly proportioned to suit atmospheric conditions. In this connection it will be noted that angularly disposed air passages 41 are provided 35 40 in the guide in close proximity to the discharge end to more thoroughly intermingle the products.
- For controlling the port 30, the needle valve 21 is provided, having a stem 42 threaded in the wall of the fitting 26 and passing through a stuffing box 43 to terminate in an operating hand wheel 44. As here shown, the port 30 is formed in a tubular plug 45 threaded into the fitting 26 45 and having a bore 46 of larger diameter than the port 30 to receive a part 47 of the valve which is somewhat larger than the diameter of the end or needle portion of the valve 21. This construction forms a means for cleaning the passage in the bushing 45, as the stem 21 can be turned to cause the part 47 and the valve needle to work back and forth in the plug passage to work out any dirt or deposits which may collect. 50 55 60 In order to retard the burning products while still obtaining the desired nozzle velocity, the inner wall of the nozzle 16 is shaped to have a curvature 48 converging in general conical form towards the nozzle outlet 50 but interrupted intermediate its

length by an annular, rounded, internally projecting shoulder 51. The function of this shoulder 51 is to gradually contract the nozzle passage so that the swirling flame will be rather abruptly changed in direction 70 and create a reverse eddy in the throat of the nozzle to fully complete the combustion and project a clean, clear reddish blue flame from the nozzle with the maximum heat intensity. 75

For rigidly supporting the burner 10, the brace or pipe 27 is bolted or otherwise made fast to the pipe 11 as shown at 52, adjacent to the handle of the apparatus. This handle consists of a sleeve or pipe 53 fitting over a portion of the supply pipe 11 but having a diameter enough larger than the pipe 11 to form an air space so that the handle portion remains relatively cool during the operation of the burner. 80

In order to place the fuel under pressure, the tank 12 is provided with a hand operated pump 54 of the plunger type actuated by a handle 55 on the exterior of the tank. As here shown the pumping element or plunger 56 embodies a pressure release mechanism comprising a check valve 57 normally held seated over a port 58 by a coil spring 60 and controlling admission of pressure to a chamber 61 which communicates with the space at the side of the plunger 56 subject to atmospheric pressure. The spring 60 is so adjusted that when the pressure in the tank 12 exceeds the desired limit, the valve 57 will be forced from its seat against the spring pressure and cause further pumping to be ineffectual. 90 95 100

A discharge pipe 62 leads from the tank 12 to a hand operated valve 63 controlling the admission of fuel to the supply pipe 11, while a filter plug 64 with a removable closure 65 serves to admit fuel to replenish the tank when empty. This plug 64 is provided with a through port 66 having a weakened section 67 which is arranged to be blown out when the pressure in the tank exceeds a certain predetermined maximum, for example, eighty pounds per square inch, and thus functions as a safety valve. 105 110

Under starting conditions it is desirable to provide an auxiliary vaporizing means arranged to operate until the nozzle parts have reached such a temperature as will cause the required continued vaporization of the fuel, and to that end the bottom portion of the burner 10 is provided with fastening devices 70 rigidly supporting a preheating pan 71. The preferred arrangement is to provide a pan 71 of a length to extend from the fuel inlet portion of the burner to the nozzle portion so that when filled with ignited fuel it will effectively heat the length of the supply pipe 11 which is just above it. Furthermore, since the shell 17 is provided with openings 38 in its bottom por- 115 120 125 130

tion, it will be evident that heat radiated from the interior of the shell will be circulated and retained by the pan in contact with the supply pipe 11 and thereby save 5 heat units otherwise lost by radiation. To increase the effectiveness of the pan 71 as a heat retainer, it is preferable to pack it with asbestos 72 or other suitable material.

From the foregoing it is believed the operation of the device will be apparent, but attention is directed to the action of the back-plate 18 and its adjuncts as these function to produce a rotary or swirling action to the incoming air which is thus thrown 10 into contact with the burning oil to thoroughly break up the gaseous content and insure perfect combustion. Also, by providing a movable mixing tube, the flame can be maintained a converging one which has its 15 focus at the desired point within the chamber of the shell or housing. By proportioning the length of the shell to that of the nozzle, and giving the latter a predetermined taper, the swirling flame attains its maximum heat just prior to being projected from 20 the nozzle outlet. The effectiveness of the flame is considerably increased because of the annular shoulder formed in close proximity to the nozzle outlet so that the gases 25 are momentarily retarded and the remaining products consumed, while the increased velocity resulting from such nozzle construction prevents the deposit of carbon and consequent choking of the outlet.

30 In connection with the mixing tube 20 the adjustable feature of this should be noted as it is possible by varying the distance of the mixing tube inlet from the discharge port 30 to change and proportion the air 35 in accordance with atmospheric conditions. Thus, for example, with a heavy atmosphere it may be necessary to increase the suction effect of the nozzle by altering the position of the tube 20 so that the distance of the 40 inlet is increased, while when conditions are the reverse, or when a wind is blowing the tube 20 is adjusted to a position somewhat closer to the port 30.

While but one form is shown in which 45 this invention may be embodied, it is to be understood that the invention is not limited to any specific construction, but might be applied in various forms without departing from the spirit of the invention or the scope of the appended claims.

Having thus described my invention, I claim:

1. In a blow torch, a casing provided with a nozzle, a fuel and air mixing tube communicating with said casing opposite to said nozzle, a valve controlled fuel supply conduit arranged to discharge into said mixing tube, means for varying the length of said mixing tube, means for supplying vaporized 55 fuel to said conduit, an air supply to said

casing, and means to proportion the supply of air to said casing.

2. In a blow torch, a casing provided with a nozzle, a fuel and air mixing tube communicating with said casing opposite to 70 said nozzle, a valve controlled fuel supply conduit arranged to discharge into said mixing tube, means for varying the distance between said discharge and said tube, means for supplying vaporized fuel to said conduit, 75 an air supply to said casing, and means to proportion the supply of air to said casing.

3. In a blow torch, a casing forming a combustion chamber, inlets respectively for vaporized fuel and air at one end of said casing, a nozzle at the opposite end of said casing, means for vaporizing fuel, a source of fuel under pressure communicating with said vaporizing means, means including a control valve for delivering vaporized fuel to said fuel inlet, means including a rotatable shutter for proportioning the air through said inlet to said combustion chamber, and means for admitting a secondary supply of air to said casing. 80 85 90

4. In a blow torch, a casing forming a combustion chamber, a fuel port arranged to discharge into said chamber, an air mixing tube adjustably mounted to move towards and away from said port, an auxiliary air supply means encircling said mixing tube, an apertured shutter connected between said casing and said tube and rotary vane members for controlling said shutter. 95

5. In a blow torch, a casing forming a combustion chamber having an open inlet end and a converging nozzle discharge end, a fuel nozzle supported in position to discharge into the open end of said combustion chamber and spaced from said end, a tubular open-ended mixing tube supported in said combustion chamber and co-axially arranged with respect to said fuel nozzle, means movably mounted in said tube for varying the air entering said tube, and means supporting said mixing tube and provided with air passages leading to said combustion chamber. 100 105 110

6. In a blow torch, a casing forming a combustion chamber having an open inlet end and a converging nozzle discharge end, 115 a fuel nozzle supported in position to discharge into the open end of said combustion chamber and spaced from said end, a tubular open-ended mixing tube supported in said combustion chamber and co-axially arranged with respect to said fuel nozzle, means movably mounted in said tube for varying the air entering said tube, and means supporting said mixing tube including air proportioning means to vary the air supply to said combustion chamber. 120 125

Signed at Philadelphia, in the county of Philadelphia, State of Pennsylvania, this 11th day of May, 1923.

HENRY HARRISON KRESS.
